UNITED STATES PATENT OFFICE.

GILBERT H. BENEDICT, OF WASHINGTON, DISTRICT OF COLUMBIA, ASSIGNOR
TO THE CENTURY PRESS COMPANY, OF WEST VIRGINIA.

MECHANISM FOR CASTING STEREOTYPES.

SPECIFICATION forming part of Letters Patent No. 437,374, dated September 30, 1890.

Application filed February 20, 1890. Serial No. 341,170. (No model.)

To all whom it may concern:

Be it known that I, GILBERT H. BENEDICT, of Washington, in the District of Columbia, have invented certain Improvements in Mechanism for Casting Stereotypes, of which the following is a specification.

This invention relates to a mechanism for use in casting stereotype-plates from matrices of papier-maché, or equivalent material, designed more particularly for the production of plates, each adapted to print a single column of matter, and each having on its back a longitudinal rib to interlock with a base-plate to which the stereotype is removably applied when in use.

My machine comprises as its essential elements a channeled base-plate to receive the matrix and type metal, a movable top plate to confine the matrix and form the top of the casting-chamber, and a laterally-movable bar, which gives form to the inside of the rib, and which by its lateral movement releases the rib to permit the removal of the stereotype.

In the accompanying drawings, Figure 1 is a perspective view of my mold or casting-box in operative position. Fig. 2 is a cross-section of the same on the lines 2 2 of Fig. 1. Fig. 3 is a top plan view of the mold as it appears when open, the top plate being shown in cross-section. Fig. 4 is a view looking into the upper end of the mold in the direction indicated by the arrow in Fig. 3. Fig. 5 is a cross-section on the line 5 5 of Figs. 1 and 3. Fig. 6 is a cross-section on the line 2 2 of Figs. 1, 3, and 7, showing the top plate slightly raised and the bar retracted laterally to release the rib of the stereotype. Fig. 7 is a longitudinal vertical section through the mold on the line 7 7 of Figs. 1, 2, 3, &c. Fig. 8 is a view looking against the under face of the upturned top plate, the bed-plate being shown in cross-section. Fig. 9 is a perspective view of a portion of the matrix-sheet. Fig. 10 is a perspective view of the stereotype.

Referring to the drawings, A represents a bed-plate mounted in an inclined position on fixed supports *a*, and provided in its upper surface with a longitudinal channel adapted to receive the matrix-sheet B and the lower face of the top plate C, which latter is connected to the lower end of the bed by slotted hinges

c, so that it may be turned upward therefrom, as shown by dotted lines in Fig. 7. The channel is somewhat wider than the matrix-sheet, and is provided in opposite sides with two longitudinal bars or bearers *D*, the inner edges of which slightly overlap the matrix, and which serve the double purpose of holding the matrix in place and of sustaining the top plate when it is in operative position, so as to accurately determine the thickness of the stereotype cast in the channel or chamber between the matrix and the top plate.

The bearers *D* have on their under faces ribs *d*, seated in grooves in the bed-plate, in order to hold the bearers from moving laterally, but admit of their being lifted sufficiently to allow the passage of the matrix-sheet thereunder. Near their inner edges the bearers are grooved longitudinally on the under side, as shown at *d'*, whereby they are adapted to fit the more tightly to the surface of the matrix, and also adapted to receive and hold beads or ribs *b*, which may be formed along the edges of the matrix. In order to force the bearers down snugly upon the matrix before the top plate is closed, pointed screws *d*² are tapped through the sides of the bed-plate in position to overlap the edges of the bearers, as shown in Figs. 1, 3, and 5; but these screws are not a necessary feature of my construction. By turning these screws backward the bearers are released, so that they may be lifted to permit the free insertion or removal of the matrix-sheet.

It is necessary that the top plate shall be held down firmly and closely upon the bearers during the casting operation, and this may be accomplished by clamping mechanism of any suitable construction. I recommend, however, for this purpose the devices shown in the drawings in which *E* represent upright pressure-screws provided with hand-wheels and tapped through yoke-bars *e*, each of which is mounted to swing around a standard *e'*, and provided at the opposite end with an open slot, so that it may swing beneath a nut *e*² on the top of a second standard *e*². The standards are fixed to opposite sides of the bed-plate, so that the yoke-bars passing over the bed-plate present the screws in position to act centrally thereon. A slight back-

ward turn of the screws releases the parts, so that the yokes may be swung back out of the path of the top plate to admit of its being raised to permit the removal of the casting and matrix. At its lower end the space or chamber between the top plate and bed is closed by a plate *g*, fixed to the bed to prevent the escape of the molten metal which is poured into the open upper end of the chamber. (Shown at 10 *h*, Figs. 1 and 4.)

In order to produce an overhanging rib of *L* form in cross-section along the back of the stereotype, as shown in Fig. 10, I form in the under face of the top plate a longitudinal groove *I* of the required shape. If this groove were formed in a solid top plate it would be manifestly impossible to remove the stereotype except by sliding it endwise, which is not a feasible plan. In order, therefore, to provide for the convenient removal of the stereotype, one side or wall of the groove—the one which gives shape to the overhanging side of the rib—is formed by a bar or plate *h'*, constituting in effect a part of the top plate and connected thereto by transverse dovetailed ribs *h²*, as shown in Fig. 7, or by like sliding connections which will admit of the bar being retracted laterally after the top plate is raised, as shown in Fig. 6.

As shown in Figs. 2, 6, and 8, the bar *h*, about midway of its length, is provided with a semi-circular depression in its upper side, into which the circular disk-head *l* of a screw *L* turns. This screw is extended laterally through a threaded opening in a sustaining bracket *M*, projecting from the side of the top plate *C*. By turning the screw in the proper direction the bar *h'* may be moved laterally on its dovetailed guides from its companion bar, and the stereotype released. By thus retracting the bar its edge or lip fitting within or beneath the rib is withdrawn therefrom, leaving the stereotype free to be lifted directly from the face of the upturned top plate.

In order to accurately determine the width of the stereotype and to produce thereon straight and parallel edges which will need no trimming or finishing, I provide the top plate with downwardly-projecting ribs *h³*, which close past the inner edges of the bearers *D* and rest tightly on top of the matrix. Although the ribs are not a necessary feature, they are highly advantageous, and their use is recommended. The top plate may have that portion of its under surface which lies opposite the bar *h'* formed in a separate piece *h⁴* and secured firmly in place, as shown in the drawings, or this portion may be formed integral with the remainder of the top plate. In order to hold the stereotype against lateral motion while this bar *h'* is being withdrawn to release the rib *I*, I provide the stationary portion with any suitable number of studs *h⁵*, which, entering the back of the plate, keep it 65 in the required position.

Owing to the fact that the molten metal is subjected on the inner surface to the chilling

effect of the metal-mold, while on the opposite surface it is in contact with the papier-mâché matrix, it is found that the metal solidifies 70 and practically completes its contraction on the upper surface before the contraction of the under surface is completed, the result being that the plate assumes on the printing-face a concave form in cross-section. In order 75 to overcome this evil, the lower face of the mold underlying the matrix is made of concave form in cross-section, the depression being at the center from one one-hundredth to one sixty-fourth of an inch. The effect of this 80 construction is to give the body of molten metal a greater thickness at the center than at the edges of the mold and to furnish surplus metal at the point where the contraction is continued for the greatest length of time. 85 The result is that the continuing contraction at the center causes the plate to assume a flat form on the printing-face.

Having thus described my invention, what I claim is—

1. In combination with the channeled bed and the movable top plate the movable intermediate bearers to confine the edges of the matrix-sheet.

2. The channeled bed and the top plate closing therein, in combination with the movable intermediate bearers, each grooved or channeled on the under side, as described.

3. The channeled bed-plate and the top plate closing therein, in combination with the intermediate bearers adapted to move vertically when the top plate is raised, and the screws acting on said bearers to hold them down upon the matrix-sheet.

4. In combination with the channeled bed-plate, the top plate having a groove therein, and a laterally-movable bar forming one wall of said groove, whereby the mold is adapted to produce and readily release a ribbed stereotype.

5. In combination with the bed and the co-operating top plate, the bar *h'*, having transverse sliding connections with the top plate, and a clamping device, as a screw, to adjust the bar laterally.

6. A mold for casting ribbed stereotypes, having the chamber to receive the metal, provided with a groove to form the rib, and made of increasing depth from the edges toward the groove.

7. In a machine for producing flat stereotypes, the bed having the channels and the bearers therein, in combination with the top plate provided with the groove and the laterally-movable bar, said plate and bar both arranged to close within the channel of the bed-plate and upon the bearers therein.

8. In a mold for casting stereotypes, the top plate forming one wall of the casting-chamber provided with the groove, the laterally-movable bar, and the studs to prevent lateral motion of the stereotype while the bar is being retracted.

9. In combination with the channeled bed-

plate and the bearers D therein, the top plate provided on its under face with the longitudinal ribs adapted to close past the inner edges of the bearers to act upon the matrix-sheet thereunder.

5 10. In a mold for casting flat stereotype-plates from non-conducting matrices, a mold-chamber having in cross-section an increasing depth from the edges toward the center.

In testimony whereof I heretofore set my hand, this 15th day of February, 1890, in the presence of two attesting witnesses.

GILBERT H. BENEDICT.
